(57) **CLAIM**

The ornamental design for a pavement marker, as shown and described.

DESCRIPTION

FIG. 1 is a front perspective view of the pavement marker taken from the front, right side and above;

FIG. 2 is a front view of the pavement marker;

FIG. 3 is a rear view of the pavement marker;

FIG. 4 is a top view of the pavement marker;

FIG. 5 is a bottom view of the pavement marker;

FIG. 6 is a left side view of the pavement marker;

FIG. 7 is a right side view of the pavement marker; and,

FIG. 8 is a bottom perspective view of the pavement marker. The broken line showing is for illustrative purposes only and forms no part of the claimed design.
